UNITED STATES PATENT OFFICE

140,445

DESIGN FOR A COMBINED BABY RATTLE AND TEETHING DEVICE OR SIMILAR ARTICLE

George I. Mims, St. George, S. C.

Application November 17, 1944, Serial No. 116,397

Term of patent 7 years

(CL. D83—1)

To all whom it may concern:

Be it known that I, George I. Mims, a citizen of the United States, residing at St. George, in the county of Dorchester and State of South Carolina, have invented a new, original, and ornamental Design for a Combined Baby Rattle and Teething Device or Similar Article, of which the following is a specification, reference being had to the accompanying drawing, forming part thereof.

Figure 1 is a front elevational view of a combined baby rattle and teething device or similar article, showing my new device,

Figure 2 is an end elevational view, and
Figure 3 is a top plan view thereof.

I claim:

The ornamental design for a combined baby rattle and teething device or similar article, as shown.

GEORGE I. MIMS.
